UNITED STATES PATENT OFFICE.

MARTIN BOURKE, OF YOUNGSTOWN, OHIO.

SASH-FASTENER.

SPECIFICATION forming part of Letters Patent No. 331,370, dated December 1, 1885.

Application filed March 2, 1885. Serial No. 157,512. (No model.)

To all whom it may concern:

Be it known that I, MARTIN BOURKE, a citizen of the United States, residing at Youngstown, in the county of Mahoning and State of 5 Ohio, have invented certain new and useful Improvements in Sash-Fasteners; and I do hereby declare that the following is a full, clear, and exact description of the same, reference being had to the annexed drawings, making a 10 part of this specification, and to the letters and figures of reference marked thereon.

Figure 1 of the drawings is a perspective view of my improved sash-fastener; Fig. 2, a side elevation of the fastener with the cap- 15 plate removed, and showing the ratchet of the bolt engaging with the ratchet-bar; Fig. 3, a sectional view of the fastener; Fig. 4, a detail view in perspective of the cap-plate of the fastener; Fig. 5, a detail view of the outer 20 side of the cap-plate; Fig. 6, a perspective view of one form of ratchet-bar, and Fig. 7 a detail view in perspective of the bolt.

The present invention has for its object to provide a simple and effective sash-fastener 25 that will securely hold the sash raised at any required height and in a closed position, and a fastener that can be easily operated, which objects I attain by the construction substantially as shown in the drawings and herein- 30 after described and claimed.

In the accompanying drawings, A represents the case for receiving the several operating parts of the fastener, said case having flanges *a* with holes therein to receive the 35 fastening-screws. To the case A is pivoted a cam, B, having a groove, *b*, therein to receive the flanged end *c* of a bolt, C. This cam B is provided with a lever-handle, D, having a fish-tail thumb-piece, E, the thumb being 40 brought to position, as at *d*, while the two fingers are brought around the inner sides of the fish-tail, as at *e*, thus enabling the lever to be more conveniently operated in either direction with increased leverage. The groove 45 *b* in the cam B is continuous and on a true circle. The pivot *f*, which eccentrically connects the cam to the case A, also connects the cap-plate F. This plate F, upon its interior, is constructed as shown in Fig. 4, the mortise 50 *g* forming a seat for the bolt C. The bolt C

has an elongated opening, *h*, through it to receive a square guide-pin, *i*, so as to prevent the bolt from rattling when operated by the lever, and guiding it in its backward and forward movement. The flanged end of the bolt 55 C, at a point where it enters the groove *b*, is made convex, so as to bring as little surface in contact with the flange of the groove as possible, in order to decrease its friction and render it more easily operated, the convexity of the 60 flanged end *c* being shown in dotted lines, Fig. 2. The bolt C, at its outer end, is provided with a ratchet-plate, G, to engage with a corresponding ratchet-bar, H, to be secured to the frame of the window. 65

The ratchet-teeth are formed in two independent rows, as shown at *k*, which renders the teeth more effective than were the teeth extended clear across the bar or plate, the space between the rows enabling the heads of 70 the fastening-screws to seat themselves without interfering with the ratchet-teeth.

The most preferable form of ratchet-teeth I have shown in Figs. 2 and 7, which are made double, each tooth of the pair inclining in opposite directions, as shown at *l*. 75

In the ratchet-teeth shown in Figs. 1 and 6, in addition to holding the sash elevated at any height, in lowering the sash, should it be let go of suddenly, the weight of the lever D 80 would force out the bolt C, and the ratchet-teeth thereon made to engage with the teeth on the bar, thus preventing the breaking of the glass in the sash by the sudden fall.

The double ratchet-teeth shown in Figs. 2 85 and 7 not only act in the same manner as described above, but lock the sash when down in either direction.

Having now fully described my invention, what I claim as new, and desire to secure by 90 Letters Patent, is—

1. A sash-fastener consisting of a suitable casing, a sliding bolt working in guides therein and slotted in the direction of its movement, a square pin passing through the case 95 and the slot in the bolt, to limit its movement and prevent oscillatory motion thereof, and a grooved cam engaging the bolt and terminating in a lever having a fish-tail thumb-piece, the parts being constructed, arranged, and 100

operating substantially as and for the purposes set forth.

2. In a sash-fastener, the combination, with a bar adapted for attachment to a window-frame, and provided with two vertical rows of double ratchet-teeth set at equal distances apart, leaving square recesses between them, each tooth being reversely inclined, of a bolt provided with similarly-formed teeth and spaces operated by a pivoted grooved cam en-

gaging with the flanged end of the bolt, substantially as and for the purpose set forth.

In testimony that I claim the above I have hereunto subscribed my name in the presence of two witnesses.

MARTIN BOURKE.
